DISPENSER FOR WRAPPING MATERIAL

Robert R. Hermann, 5 Bridle Road, La Due, Mo.

Filed May 4, 1964, Ser. No. 79,802

Term of patent 14 years

(Cl. D52—2)

FIG. 1.

FIG. 2.

FIG. 3.

FIG. 4.

FIG. 1 is a plan view of a dispenser for wrapping material incorporating my new and original design,

FIG. 2 is an elevational view of the left-hand side of the dispenser shown in FIG. 1,

FIG. 3 is a front elevational view of the dispenser shown in FIGS. 1 and 2, and

FIG. 4 is a bottom view of the dispenser shown in FIGS. 1-3.

In FIG. 1 the shading in the areas indicating a conventional fabric is understood to be repeated throughout such areas, and in FIG. 3 the shading in the turned-in flap areas indicating a conventional fabric is understood to be repeated throughout such areas.

I claim:

The ornamental design for a dispenser for wrapping material, as shown and described.
